UNITED STATES PATENT OFFICE

THEODORE G. FALSTROM, OF WEST ORANGE, NEW JERSEY, ASSIGNOR TO MONROE CALCULATING MACHINE COMPANY, OF ORANGE, NEW JERSEY, A CORPORATION OF DELAWARE

MEANS FOR SETTING DIES IN PRESSES

Application filed January 4, 1930. Serial No. 418,591.

The invention has relation to power presses and particularly to means for setting or aligning dies in presses. An object of the invention is to eliminate the use of liner or dowel pins. Another object of the invention is to provide such an aligning means which is more adapted to the standardization of design in punch press tools. Another object is to reduce the cost of die shoes and punch holders. Another object is to eliminate possibility of the tools shifting out of alignment while the press is being operated. Another object is to provide greater accessibility for the tools with less hazard to the operator and to speed up production. Another object is to effect a saving in tool cost on certain types of tools. Another object is to reduce the skill required on the part of the die setter. Another object is to improve the operation of power presses having a pillar-guided slide. Another object is to make more effective the use of safety appliances attached to the press for the purpose of preventing injuries to the operator.

The invention is particularly adapted for use with the new type of press wherein the slide is guided on four guide posts or pillars sliding in bushings adjustable for wear, but can also be used on presses of the conventional design.

The invention consists in the novel construction and combinations of parts as set forth in the appended claims.

In the accompanying drawings illustrating an embodiment of the die setting means, Figure 1 is a front view of a punch press having my die setting means applied thereto;

Fig. 2 is a detail top plan view of the lower die holder and die;

Fig. 3 is a detail bottom plan view of the upper die holder and die;

Fig. 4 is a perspective detail view of the lower die holder having the die removed therefrom;

Fig. 5 is a similar view of the lower die;

Fig. 6 is a similar view of the upper die holder; and

Fig. 7 is a similar view of the upper die.

In these drawings, the numerals 1 and 2 designate top and bottom master bolsters

which may be either a part of the press, or attached thereto so that there is no possibility of shifting to disturb the alignment of the parts to be described. These top and bottom master bolsters constitute upper and lower die holders, and are both cross-milled with channels 3 and 4 intersecting at right angles, and wherein fit cross-keys 5 and 6, the outer halves or portions of which fit in similar cross-channels 7 and 8 of the upper die or punch 9 and the lower die 10. These cross-keys and channels as shown are of rectangular form in cross section.

It is, of course, essential that the cross-channels of the upper and lower die holders and dies be accurately aligned with one another and in order that this may be done, the following method is employed.

The top or the bottom die holder and die are milled with the cross-channels in quantity, said channels intersecting at right angles as stated. The milling of the other or matching die holders and dies however is done after the tools or dies have been mounted on their shoes or holders and the punch or upper die entered into the lower die. The entire unit is then clamped together and placed in a simple fixture on which the cross-channels already milled are aligned with the milling cutter for the cross-channels to be milled. The set up of this means is readily accomplished with the aid of a simple gauge and as the work does not require any great amount of skill, it may be done very economically.

On presses which have dovetail slides and where there is difficulty in maintaining an accurate adjustment, it would be necessary to equip the press with a master liner pin die set. This same die set, being equipped with keys to fit the channels in the upper and lower die holders could be used with any number of different dies, making it unnecessary to use a separate liner pin set for each set of tools.

I claim:

1. Means for setting dies in presses, comprising upper and lower die holders and dies, each die holder and its related die having in the contacting faces thereof transverse aligned recesses forming a transverse chan-

nel, and transverse aligning keys fitting in the channels.

2. Means for setting dies in presses, comprising upper and lower die holders and dies, each die holder and its related die having in the contacting faces thereof transverse aligned recesses forming transverse channels angularly related to each other, and transverse keys also angularly related to each other fitting in said channels.

10 3. Means for setting dies in presses, comprising upper and lower die holders and dies, each die holder and its related die having in the contacting faces thereof transverse aligned recesses forming transverse channels angularly related to and intersecting each other, and transverse aligning keys also angularly related to each other fitting in said channels.

15 4. A die set, comprising upper and lower die holders, a set of interchangeable upper dies and a set of interchangeable lower dies, each die holder and its related dies having in the contacting faces thereof transverse aligned recesses forming a transverse channel, and transverse aligning keys fitting in the channels.

20 5. A die set, comprising upper and lower die holders, a set of interchangeable upper dies and a set of interchangeable lower dies, each die holder and its related dies having in the contacting faces thereof transverse aligned recesses forming transverse channels angularly related to each other, and trans-
25 verse aligning keys also angularly related to each other and fitting in said channels.

30 6. A die set, comprising upper and lower die holders, a set of interchangeable upper dies and a set of interchangeable lower dies, each die holder and its related dies having in the contacting faces thereof transverse aligned recesses forming transverse channels angularly related to and intersecting each other, and transverse aligning keys also angularly related to each other fitting in said channels.
